THERMOSTAT CONTROL

Application filed February 25, 1929. Serial No. 342,651.

The present invention relates to improvements in thermostat controls, and its object is to provide a particularly sensitive thermostat for controlling an electrical circuit including a current-consuming device, as, for instance, an electrical heater.

More particularly, it is proposed in the present invention to utilize for the purpose of obtaining a sensitive thermostat two bimetallic spirals, the inner ends of which are mounted on spaced posts, while the outer ends are interconnected, preferably in such a manner as to place both of the spirals under slight tension, which causes the connection to snap across a medial line under the influence of changes in temperature.

It is further proposed in the present invention to mount the posts in such a manner that by a slight turning motion of the same, the tension of the two spirals may be changed, so that the same may be made to become responsive to different degrees of temperature.

It is further proposed to provide means allowing the spacing between the two posts to be changed for adjustment purposes.

Further objects and advantages of our invention will appear as the specification proceeds.

The preferred forms of our invention are illustrated in the accompanying drawing, in which

Figure 1 shows a top plan view of one form of thermostat;

Figure 2, a side elevation of the same;

Figure 3, a side elevation of a modified form of our thermostat; and

Figure 4, a top plan view of the same.

While we have shown only the preferred forms of the invention, we wish to have it understood that various changes or modifications may be made within the scope of the claims hereto attached without departing from the spirit of the invention.

In the forms shown in Figures 1 and 2, our thermostat consists of a base 1 of insulating material having mounted thereon, in spaced relation, two small plates 2 somewhat elongated in form, each fastened to the base by means of two screws 3 and 4, the latter of

so that each plate may be swung about the screw 3 as a pivot, while the screw 4 rides in the slot 6. Each of the plates 2 has extending upwardly from a central section thereof and with freedom of turning motion a post 7, and each post has fastened thereto the inner end of a spiral 8, which latter is bimetallic and may be made, for instance, of adjacent layers of invar and brass. The free ends of the two spirals are interconnected by means of a hinge 9. It should be observed that the connection between the two spirals should be such as to place the spirals under slight tension, which is preferably accomplished by positioning the spirals in such a manner that normally their loose ends would slightly overlap and therefore have to be slightly pushed back for affecting the hinged connection. The metals should be arranged in the two spirals in such a manner that after they have been connected, the same metals are presented on the same sides. The post 7 of each spiral has an arm extending therefrom, and these two arms 11 and 12 are interconnected by means of a pin 13 extending downwardly from the arm 12 into a slot 14 provided in the arm 11. By operation of one of these arms, a turning motion may be imparted to the two posts 7 for adjusting the tension of the two spirals, and the friction between the pin 13 and the arm 11 is sufficient to hold the two arms in adjusted position.

The section 16 of one of the spirals adjacent the hinge 9 carries contacts 17 and 18 on opposite faces thereof adapted to engage with contacts 19 and 21 disposed on opposite sides of the section 16 in spaced relation to one another.

The operation of the device thus far described is as follows: If the thermostat is intended to become active at certain maximum and minimum temperatures, the two spirals are tensioned by operation of the plates 2 for spacing the posts and the handles 11 and 12 for revolvably adjusting the posts, so that at the maximum temperature, the point 18 will contact the point 21, and at the minimum temperature, the section 16 will snap over the medial line to contact the point 19. 100

It should be understood that this thermostat is very sensitive, due to the light structure of the spirals, while at the same time, it is very substantial and even rugged in its operation, since the two loose ends of the spirals are interconnected and are thereby prevented from vibrating. It will respond immediately to changes in temperature, but will not easily vibrate in response to jarring motions, and this feature would make the thermostat adapted for use on moving vehicles, for instance.

The thermostat illustrated in Figures 3 and 4 is intended for finer adjustments in the spacing as well as the turning of the two posts on which the spirals are carried.

It consists of two standards 22 rising from the base 23, a horizontal rod 24 supported in the two standards and posts 25 slideable on the rods.

The two posts may be advanced toward one another by means of screws 26 passing through the standards 22 and may be held in adjusted position by means of set screws 27. An operating rod 28 extends through the two standards and the two posts and is formed with a suitable handle 29.

The two posts 25 have pins 31 extending upwardly therefrom on which are mounted sleeves 32. These sleeves have the inner ends of the two spirals 8 fastened thereto, and the spirals are interconnected by the hinge 9, as previously described. Each of the sleeves carries a cog wheel 33, and the two cog wheels mesh with two pinions 34 fastened on the operating rod 28.

It will be seen that in this construction, the two sleeves holding the inner ends of the two spirals may be turned by manipulating the operating rod 28, while the spacing between the two posts 25 may be adjusted through manipulation of the screws 26 and 27. This apparatus is capable of very fine adjustment and will respond to very slight changes in temperature.

It should be understood that while the spirals such as shown in the drawing seem particularly adapted for our purposes, particularly due to the fact that a considerable length of metal may be accommodated in a small space, simpler forms might suffice for certain purposes, such as spirals of a single turn, or of even less than a single turn or possibly even straight bimetallic strips as long as they are made sufficiently resilient or mounted with sufficient resiliency to snap across a medial line.

We claim:

1. In a thermostat control of the character described, two bimetallic lengths of spring material mounted in spaced relation with their free ends tending to overlap along the centerline and a connection between the free ends adapted to place the two lengths under tension whereby the connection is made to

snap across the centerline in response to changes in temperatures.

2. In a thermostat control of the character described, two bimetallic lengths of spring material, two posts mounted in spaced relation, each having one end of the said lengths attached thereto so that the two free ends tend to overlap along the centerline of the posts, a connection between the free ends adapted to place the said lengths under tension and means for revolvably adjusting the two posts.

3. In a thermostat control of the character described, two bimetallic lengths of spring material, two posts mounted in spaced relation, each having one end of the said lengths attached thereto so that the two free ends tend to overlap along the centerline of the posts, a connection between the free ends adapted to place the said lengths under tension, means for revolvably adjusting the two posts, and means for adjusting the spacing between the two posts.

4. In a thermostat control of the character described, two bi-metallic spirals having radial outer ends, means for mounting the inner ends of the spirals in spaced relation so as to cause the outer ends to extend toward one another in a central plane and means for interconnecting the free ends so as to place both spirals under compression for causing the end pieces to snap across the center line in response to temperature changes.

5. In a thermostatic control of the character described, two bimetallic lengths of spiral spring material having their inner ends anchored in spaced relation, said spirals having outer integral end portions bent to extend radially and to substantially lie in the centerline of the anchors, a connection disposed between the radially extending portions, and with said portions serving to place said spirals under a compression force, whereby the radial portions are made to snap across the center line in response to temperature changes.
